HOROLOGICAL DEVICE

Johan Machek, Waukegan, Ill.

Application November 9, 1935, Serial No. 48,949

7 Claims. (Cl. 40—111)

The present invention relates in general to a horological device and is particularly concerned with improvements in a calendar mechanism for automatically indicating the current date.

5 Applicant is aware that devices for this general purpose have heretofore been constructed, but the prior art devices have in the main been objectionable in that they did not automatically compensate or correct for "leap year" and for 10 the variation in the number of days in the respective months of the year. It was therefore necessary to occasionally make this correction manually, in order that the date indicated would be correct.

15 Having in mind the disadvantages and objections to the prior art devices, the present invention contemplates an improved calendar mechanism wherein the current "day of the week", "day of the month" and the "month of 20 the year" will be automatically disclosed, and in which the mechanism is so constructed that the date denoting indicia will be automatically changed in such a manner as to compensate for "leap year" and the variations in the number 25 of days in the respective calendar months.

25 A further object of the invention is to provide a horological device having indicating hands and a dial, similar to those of a conventional clock, which is adapted to automatically indicate the current date.

30 A further object is to provide a horological device of the herein-described type, wherein the date indicating indicia are automatically changed with a jump or snap action from one indicium to another.

35 A further object is to provide in a date indicating device improved automatic mechanism for actuating and controlling the change of the date indicating indicia so as to correctly denote the 40 current date at all times.

45 A still further object of the invention is to provide novel means for compensating for "leap year" and the variations in the number of days constituting the respective calendar months.

50 It is also an object to provide a date indicating mechanism of such construction that it may be utilized as an attachment for a time indicating device, such as a clock, and when so attached its operation will be controlled by the time keeping device.

55 In accordance with the general features of the present invention it is proposed to provide a horological device having two adjacently disposed dials. One of these dials is provided with conventional clock time indicating indicia and

is traversed by the conventional hour and minute hands as in the ordinary clock, for indicating the time of the day. The other dial is provided with two concentric circular scales which are respectively traversed by hands similar to the hour and minute hands of the ordinary clock. The outermost of these scales has thirty-one 10 equally spaced graduations bearing numerals from one to thirty-one, inclusive, for indicating the "days of the month"; while the innermost scale has twelve equally spaced graduations bearing numerals from one to twelve, inclusive, for indicating the "months of the year".

Corresponding to the conventional second hand of a clock, the latter dial also is provided with 15 a similar hand, this hand traversing a circular scale having seven equally spaced graduations bearing numerals from one to seven, inclusive, for indicating the "days of the week". While, in the disclosed embodiment of the invention, numerals 20 have been utilized to indicate the days of the week and the respective months, it is contemplated that letters or other suitable indicia may be utilized, if desired.

The clock and date indicating portions of the 25 device are respectively provided with their own individual operating mechanisms, and these two mechanisms are interconnected by means of a link so that the operating mechanism of the clock will control, through suitable tripping 30 means, the operation of the date indicating mechanism at predetermined time intervals, in this case every twenty-four hours.

An additional feature of the invention resides 35 in an improved mechanism for moving an indicating hand with a snap action from one scale indicium to another. For this purpose, a pair of gears is adjacently mounted for rotation on a common arbor. These gears are interlocked by means of loosely meshing alternately disposed 40 projections which permit limited relative rotational movement of the gears. Moreover, these gears are flexibly interconnected by means of a spring so that one of these gears may be slowly advanced while the other is held against movement. This action tensions the spring and stores up energy which is available, upon the release 45 of the previously held gear, to advance the same with a snap action through the limited distance 50 relative to the gear that was first moved. By mounting an indicating hand for movement with the spring actuated gear, this hand will likewise be moved with a snap action. The gears are latched, advanced and released by means of suit- 55

able pawls as will hereinafter be more specifically described in detail.

Other objects and features of the invention will more fully appear from the following detail 5 description taken in connection with the accompanying drawings which illustrate a single embodiment thereof, and in which:

Figure 1 is an elevational view of a horological device embodying the features of the present 10 invention;

Figure 2 is a side view of the mechanism for actuating the hands of the date indicating portion of the device;

Figure 3 is a vertical sectional view of the 15 mechanism taken substantially on line III—III of Figure 2;

Figure 4 is a fragmentary sectional view showing 20 details of the instrumentalities of the "day of week" mechanism;

Figure 5 is an elevational view of the mechanism showing the instrumentalities for the "month of year" indication;

Figure 6 is an enlarged fragmentary sectional 25 view showing details of certain parts of the same, taken substantially on line VI—VI of Figure 2;

Figure 7 is an enlarged sectional view taken 30 substantially on line VII—VII of Figure 6, and having cut away portions to show details of construction;

Figures 8 and 9 are enlarged fragmentary plan 35 views partly in section and having cut away portions to illustrate the escapement releasing and latching mechanism; and

Figures 10, 11, 12, and 13 are views diagrammatically illustrating the operation of the master gear for automatically compensating for leap 40 year and a variable number of days in the calendar months.

As shown on the drawings:

40 Figure 1 of the drawings discloses a horological device, generally indicated by the number 15, which embodies a time indicating dial 16 and a date indicating dial 17. The dial 16 has associated therewith the conventional hour hand 18 and minute hand 19 which are driven by means of a clock mechanism of the conventional type.

The dial 17 at its peripheral margin is provided with two concentrically disposed scales 20 and 21. The inner of these scales contains indicia such 50 as numerals from 1 to 12 inclusive, these numerals being equally spaced circumferentially of the dial and cooperating with a hand 22 to indicate the respective months of a year, the outermost dial 21 is composed of equally spaced and circumferentially extending numerals from 1 to 31 inclusive which cooperate with an indicating hand 23 to indicate the days of a month. Disposed above the axis of rotation of the hands 22 and 23 is a small hand 24 which traverses a relatively 55 small circular scale 25 bearing indicia from 1 to 7 inclusive for indicating the respective days of the week. The hands 22, 23, and 24 are driven by means of an operating mechanism which is, except for features of control to be later explained, separate and apart from the clock mechanism.

It is therefore evident that an observer may 70 by viewing the two dials of the device easily ascertain the "month of the year", the "day of the month", the "day of the week" and the "time of the day". The indications on the date dial are automatically changed and the mechanism is so constructed as to automatically compensate for leap year and for the variable number of days 75 of the month. Although numerals have been

utilized in the disclosed embodiment of the invention, it will be readily apparent that any other suitable indicia may be used without departing from the concepts of the present invention.

The mechanism for actuating the hands 22, 23, 5 and 24 is operatively associated with and the various instrumentalities thereof are mounted on spaced front and back plates 26 and 27 which are secured together by spacer posts 28 to form a frame structure.

The driving means in this case is a spring motor which is of the conventional type comprising a spring drum 29 which houses a spring (not shown), one end of this spring being connected to the drum and the other end connected to a 15 shaft 30. Associated with the winding drum 29 for unitary movement is a driving gear 31. The drum and gear are rotatable relative to the shaft.

The shaft 30 is rotatably mounted in the plate members 26 and 27 and terminates at one end in 20 a key stem 32 adapted to receive a winding key. This shaft also carries a ratchet wheel 33 which permits rotation of the shaft 30 in a direction to wind the driving spring, and is held against reverse movement by a check pawl 34 which is 25 normally actuated by means of a spring 35 into engagement with the teeth of the ratchet wheel.

The driving gear 31 meshes with a pinion 36 which is rotatable with a shaft 37 having its ends 30 rotatably mounted in the plate members 26 and 27.

Rotation of shaft 37 under the impulse of the driving motor is controlled by an escapement of the anchor type. The shaft 37 carries an escapement wheel 38 having thirty-one teeth. Ad- 35 vancement of the escapement wheel is controlled by pallets 39 and 40 which are disposed on opposite sides of a pivotal support 41 of a pallet supporting arm 42.

The pallets 39 and 40 are actuated once every 40 24 hours to normally advance the escapement wheel one tooth. This is accomplished by means of a release and latch mechanism which is controlled from the mechanism of the adjacent clock or time indicating element of the device comprising this invention.

For this purpose there is provided in connection with the clock mechanism a rotatable disc or gear 43, as shown in Figure 4, this gear being arranged to make one complete revolution in twenty-four 50 hours. The gear 43 carries a pin 44 which is spaced outwardly of the center of rotation of the gear and extends into a slot 45 of a reciprocable lever 46. This lever is pivotally connected as shown at 47 to the outer end of a main arm 48 which is fixedly secured at its other end to a rotatably mounted shaft 49 so that once every twenty-four hours the shaft 49 will be rotated a limited distance in one direction and then in the opposite direction.

There is also mounted on the shaft 49 for rotation therewith a heart-shaped jaw supporting member 50 which supports a pair of jaws 51 and 52. These jaws, which are of different lengths, are spaced apart and pivotally mounted on the 65 supporting member by pivot pins 52 and 53 respectively. A tension spring 54 interconnects the jaws 51 and 52 and acts to pull them towards each other until restrained by stop pins 55 and 56 respectively engaging associated abutment lugs on the jaw supporting member. These jaws are free to be moved apart relative to each other against the tension of spring 54.

The escapement wheel is normally latched against movement by the engagement of an abut- 70 75

ment block 57 on the pallet supporting arm with the outer end of the longer of the jaws 51, as shown in Figure 3.

It will be observed that as the disc 43 continues 5 to move, the pin and slotted link connection will cause the arm 48 to slowly move in a clockwise direction, whereupon the jaw 51 will disengage the block 57, and since the jaws are also being moved in a clockwise direction, the block 57 will be 10 moved into engagement with the outer end of the shorter jaw 52.

As the arm 48 begins to move in the opposite direction or counter-clockwise, the block 57 will engage the overlapping end of the jaw 51 and 15 gradually cause it to be forced away from its normal position until a point is reached wherein the block may move between the jaws 51 and 52. This action permits the pallets to operate and 20 advance the escapement wheel one tooth. During this operation the block 57 will be moved outwardly from between the jaws 51 and 52, and when this happens, the spring 54 which has been tensioned will again pull the jaws towards each other and the block 57 will be latched against further 25 movement in a direction towards the jaws, until such time as the arm 48 is again shifted in a clockwise and then counter-clockwise direction.

"Day of week" mechanism

30 The day of the week is indicated by hand 24 which is moved from one indicia to the next with a snap action. Movement of this hand is accomplished once every twenty-four hours by the mechanism as shown in Figure 4. A pair of gears 58 and 59 are mounted for coaxial rotation in the end 35 of a supporting block 60a, each gear having angularly disposed teeth, in this case seven teeth each, which extend in opposite directions. The gears 58 and 59 are loosely coupled in the same manner 40 as the gears for actuating the day of the month indicating hand 22, which will subsequently be explained in detail. In general, the gears 58 and 59 have loosely meshing and alternating projections which permit limited movement of one gear 45 relative to the other. The gears are also connected to the respective ends of a coiled spring so that if one gear is held stationary while the other is rotated a limited amount, the first gear when released will move with a snap action through the 50 distance the other gear has been moved. More specifically, the arrangement for moving these gears comprises a hook pawl 60 having one end pivoted at 61 to the arm 48. This pawl is normally biased against rotational movement in a 55 counter-clockwise direction by means of a spring 62, this spring tending to maintain an abutment 63 on the pawl in engagement with a stop pin 64 on the arm 48. The hook end of the pawl engages the teeth of gear 59, and since this gear is provided with seven teeth, it will be apparent that 60 each time the arm 48 is moved, this movement taking place once every 24 hours, the gear 59 will be shifted one tooth. This action energizes the spring connecting the gears 58 and 59, and gear 59 65 is retained in the advanced position by means of a slip pawl 65 which is pivotally supported in the block 60 and has its gear engaging end biased against movement away from the gear by an expansion spring 66. The gear 58 is latched against 70 rotational movement in a counter-clockwise direction as viewed in Figure 4, by means of a latching lever 67 having a pin 68 which is disposed between the teeth of the gear when the latching lever is in latching position. Movement of the latching lever 67 about its pivot 69 in a direction to move 75

the latch pin 68 to unlatched position, is opposed by a spring 70 having its outer end anchored to the plate 26 as shown at 71.

Since the movement of arm 48 also releases the escapement mechanism once every twenty-four 5 hours, advantage may be taken of the movement of the pallet supporting arm 42 to move the latching arm 67 to unlatched position. This is accomplished by providing a pin 72 on the latching arm 67, which is engaged by the pallet supporting arm, 10 when the pallet supporting arm is moved in a counter-clockwise direction. This movement of the arm 42 will shift the latching arm 67 against the force of spring 70 and move the latch pin 68 from between the teeth of gear 58, thereby letting 15 this gear move with a snap action to advance the hand 24 to the next succeeding day of the week indicating numeral.

The gear 58 is secured to a shaft 73 which is rotatably mounted in the plate 26 and has the 20 hand 24 fixedly secured to the outer end thereof.

"Month of year" mechanism

Due to the similarity in the manner of operation of the hand 22 for indicating the respective days 25 of the month, this mechanism will now be described.

As before stated, the escapement wheel 38 is provided with thirty-one teeth corresponding to a month having a maximum number of days. By 30 means of a correcting mechanism for compensating for months having less than thirty-one days, the escapement wheel will be moved through one complete revolution each month, regardless of the number of days in the month. Correspondingly, 35 the shaft 37 will also make one complete revolution each month.

As in the case of the gears 58 and 59 which are utilized in operating the day of the week indicating hand 24, the hand 22 is actuated in a similar 40 manner by gears 74 and 75. The details of interconnecting these gears are clearly shown in Figures 6 and 7.

One end of shaft 37 extends outwardly of plate 26 and has rotatably mounted thereon a sleeve 45 76 which at its inner end abuts a shoulder 77 formed in the shaft. This sleeve has secured to its outer end as by a screw 78, the hand 22. The inner end of this sleeve has the gear 74 rotatably mounted thereon. The gear 75 is fixedly secured 50 to the sleeve for rotation therewith.

The gears 74 and 75 are each provided with twelve teeth which on the two gears extend relative to each other in opposite directions. These gears are provided with loosely meshing projecting portions 79 and 80 respectively which permit limited rotational movement of the gears. A coiled spring 81 is disposed in confronting circumferential grooves 82 and 83 of the gears 74 and 75 respectively, one end of this spring being 60 anchored to the gear 74 and the other end being anchored to the gear 75.

The shaft 37 has fixedly mounted thereon a cam member 84 which is adapted when rotated to successively engage an arm 85 and an arm 86. The 65 arm 85 is fixedly secured at one end to a shaft 87 which is rotatably mounted in the plates 26 and 27. The arm 86 is secured at one end to a shaft 88 which is rotatably mounted in the plate members 26 and 27.

The arm 86 is normally held in engagement with a stop pin 89 by means of a spring 90 which is anchored at its free end to plate 26 as shown at 91 and is secured at its other end to the shaft 88. Secured to the shaft 88 and outwardly dis- 75

posed relative to plate 26 is an arm 92. This arm at its outer end has pivotally mounted thereon a push pawl 93 which is normally actuated by a spring 94 into engagement with the teeth of gear 74. It will therefore be evident that when the arm 86 is moved by the cam member 84 in a counter-clockwise direction, the push pawl 93 will act to advance gear 74 one tooth. The gear 74 is retained in the advanced position by means of 10 a slip pawl 95 which is constructed of spring material.

The arm 85 is normally held against a stop pin 96 by means of a spring 97 having its ends respectively connected to a hook latch 98 and an 15 anchor 99 on the plate 26. This spring acts to cause the hook latch to move in a clockwise direction so as to normally engage the teeth of gear 75 to prevent rotation of the gear in a clockwise direction. When, however, the hook latch 98 is 20 released by virtue of the cam member 84 engaging the arm 85, the gear 75 is free to move and advance the hand 22 to the next month indicating numeral.

It will be obvious that since the cam 84 makes 25 a complete revolution with the shaft 37 during each month, advantage of the movement of this wheel may be taken to first advance the gear 74 to tension the spring 81 so that when gear 75 is released at the end of the month, the hand 22 will 30 be moved with a snap action.

"Day of month" mechanism

Since the escapement wheel 38 is provided with thirty-one teeth and is advanced one tooth every 35 twenty-four hours, it is only necessary to secure the indicating hand 23 to shaft 37 in order that this hand shall be moved one indicia each day of the month. The escapement wheel will be advanced twenty-eight, twenty-nine, thirty and 40 thirty-one steps in single tooth movements respectively, depending upon whether or not the month has twenty-eight, twenty-nine, thirty or thirty-one days therein. In order that the escapement wheel shall make a complete revolution 45 each month regardless of the number of days therein, it will be evident, for example, that in a twenty-eight day month, the indicating hand will have to move from numeral twenty-eight to numeral one. In other words some means must 50 be provided for augmenting the normal advancement of the wheel so that at the end of the respective month, the indicating hand will move a distance corresponding to four teeth on the escapement wheel for a twenty-eight day month, three teeth for a twenty-nine day month, two teeth for a thirty-day month and will move one tooth for a thirty-one day month in going from the last day of any given month to the first day of the next succeeding month.

60 The single tooth step advancement of the escapement wheel 38 and consequently the hand 23 is augmented at the end of the month to automatically compensate or correct for the variable number of days in the respective calendar months 65 and for leap year. This is accomplished through the provision of a forty-eight tooth master gear 100 which is rotatably mounted on a gear plate 101.

70 The gear plate is secured to a shaft 102 which is rotatably mounted in the plate members 26 and 27. It will be observed that this shaft forms a center of rotation for the plate 101 which is outwardly spaced from the periphery of gear 100, thereby permitting the plate 101 and gear 75 100 to be rotated as a unit with the center line

of shaft 102 as their center of rotation. On the opposite side of the shaft 102 from the plate 101 and gear 100 is an oppositely projecting lug 103 which has a tension spring 104 connected at one end thereto. The other end of the spring 5 104 is anchored as shown at 105 to the plate member 26. On the opposite side of shaft 102 from the lug 103, the plate 101 is provided with an outwardly projecting lug portion 106.

Normally, the spring 104 has a tendency to 10 rotate the plate 101 in a counter-clockwise direction and resiliently retains the same against movement in a clockwise direction. Movement of the plate in the first direction is opposed by engagement of lug 106 with a stop pin 107 which 15 is mounted in the plate 26.

A pin 108 is carried by the escapement wheel 38 and is so arranged that as the escapement wheel is revolved, this pin is brought into engagement with the lug 106, with the result that 20 the plate 101 is shifted in a clockwise direction until the pin 108 disengages the lug. The plate now being released, the spring 104 forces the plate to move in the opposite direction until the lug again engages the stop pin 107. It will therefore be evident that each month of the year, the plate 101 will thus be shifted.

Advantage is taken of this shifting movement of the plate 101 to actuate the master gear 100 so that it will be advanced one tooth each month. 30

Advancement of the master gear is accomplished by means of a push pawl 109 which is pivotally mounted on the frame 26 and actuated by a spring 110a into resilient engagement at its free end with the teeth of the master gear. 35 Upon clockwise movement of the plate 101, the pawl 109 will move into engagement with the following tooth, and movement of the plate to normal position against the stop pin 107 will cause the master gear to be rotated about its axis the distance of one tooth. The master gear is held in shifted or advanced position by a slip pawl 110 which is constructed of resilient material and secured at one end as by a screw 111 to the plate 101.

The plate 101 also carries an arm 112 which is pivotally mounted on the plate as shown at 113 for swinging movement. This arm is arcuate in form and at its free end is provided with a stop pin 114 which normally engages the outer edge of the plate to limit counter-clockwise movement of the arm about its pivot under the influence of a leaf spring 115 which is secured at one end to the arm and is held in flexed position by a pin 116. This pin is mounted in the 55 plate 101.

The outermost end of the arm 112 carries a pin 117, which is adapted under certain conditions depending upon the position of lever 112, to engage an abutment flange or shoulder 118 formed on the outer end of an arm 119, when the plate 101 is shifted in a clockwise direction.

The engagement of the pin 117 with this shoulder will cause a clockwise movement of arm 119.

The arm 119 is integrally formed with the jaw 65 51. The jaws 51 and 52 are interconnected by means of a pair of overlapping fingers 120 and 121 which are respectively integrally formed with the jaws 51 and 52. Now, it will be observed, that if the jaw 51 is rotated in a clockwise direction, this movement through the fingers 120 and 121 will cause both jaws 51 and 52 to be moved outwardly against the pressure of spring 54 a sufficient amount to enable the block 57 to freely move in and out between the jaws and 75 52.

permit operation of the escapement wheel 38. This position of the jaws is clearly shown in Figure 9. The advancement of the escapement wheel will continue until the pin 108 disengages the lug 106 and permits the plate 101 to move in a counter-clockwise direction to normal position.

It will now be evident that the free movement of the escapement will always be terminated at the same time, that is, when the pin 108 disengages the lug 106. Also that the beginning of the free movement condition will be advanced or retarded depending upon the position of arm 112. By shifting the arm 112 in a clockwise direction, in which case the stop pin 114 is moved outwardly from the associated edge of the plate 101, the pin 117 may be caused to engage the shoulder 118 at an earlier or later time after the beginning of the shifting movement of the plate 101 by the pin 108. The position of the lever 112 will therefore determine the length of time that the jaws 51 and 52 will be in wide open position, and consequently the number of teeth that the escapement wheel will advance during the free movement of the block 57. The position of the arm 112 is determined by a plurality of pins which are carried by the master gear 100 and engage a projection 122 formed on the arm 112.

Referring to Figure 8, which shows the mechanism in normal position with the jaw 51 latching the block 57 against movement, it will be observed that some of the pins on the gear 100 are disposed a greater distance from the center of the gear than other of the pins. Some of these pins, such as the pin 123, are disposed on a pin circle 124. Other of the pins, such as pin 125, have their centers disposed on a pin circle 126 which is slightly further from the center of the gear than pin circle 124. Also pins such as pin 127 are on pin circle 128 which is of still greater diameter.

It will also be observed that these pins are in each case placed on a tooth radius and that in the case of some of the teeth on the gear 100, there are no pins on the radii of the teeth. In these cases, the projection 122 would not be engaged by a pin and the arm 112 would be moved clockwise to its stop position.

In general, when the projection 122 is in a space or does not engage any pin, the mechanism will indicate the days for a thirty-one day month. When the projection 122 engages a pin on the pin circle 124, as shown in Figure 11, the mechanism will indicate a thirty-day month. When the projection 122 engages a pin on the pin circle 126, the mechanism will indicate a twenty-nine day month as shown in Figure 12. When the projection 122 engages a pin lying on the pin circle 128, a twenty-eight day month will be indicated, this position being shown in Figure 13. It will therefore be evident that the pins may be so distributed on the gear 100 as to take care of all the months of a four-year period and thus compensate for the variations in the number of days in the respective months and also leap year. The master gear will therefore make one complete revolution every four years.

Figure 8 shows the normal position of the plate 101 against its stop pin 107 with the pin 108 just engaging the lug 106 to cause shifting of the plate. The master wheel is in position for a thirty-one day month, the projection 122 being disposed in a space. It will be ob-

served that the pin 117, during shifting of the plate 101, will have to move its greatest distance before it engages the shoulder 118 to open the jaws 51 and 52. Under these conditions, the escapement wheel 38 will continue to advance in one-tooth steps and pin 117 will continue to approach the shoulder 118 until pin 108 has reached the position shown in dotted lines 108-C in Figure 10. As the pin 108 moves from position 108-C to 108-D, the pin 117 will approach but will not strike the shoulder 118 to open the jaws 51 and 52. The pin 108 will disengage the lug 106 and permit the plate 101 to return to normal position. At the same time, the arm 48 will have shifted in a clockwise direction sufficiently to disengage the jaw 51 from the block 57 and will have moved in a counter-clockwise direction sufficiently to have released the jaw 52 relative to the block 57, whereupon the block will pass between the jaws and then move outwardly to latched position as shown in Figure 3. In other words for a thirty-one day month, the jaws are not opened by actuation of the tripping lever 119, but the escapement wheel is advanced one tooth as in the normal manner of operation through the actuation of arm 48 as heretofore described in detail. The hand 23 in this case will move from the numeral thirty-one to the numeral one to begin the new month.

Referring to Figure 11, the shifting of the plate 101 will have advanced the master gear one tooth, and if the next month is to be a thirty-day month, the projection 122 will be engaged by a pin 123 on the pin circle 124. This will move the pin 117 a little closer to shoulder 118. Under these conditions, when pin 108 reaches the dotted line position 108-B as shown in Figure 10, pin 117 will engage the shoulder 118 and open the jaws as shown in Figure 9. This will enable the escapement wheel to continue moving until pin 108 reaches position 108-D, whereupon the plate will be released as before and returned to normal position, and the jaw 51 will again latch the block 57 against further movement. The hand 23 will have jumped from numeral thirty to numeral one to begin the next new month.

If the next month is to be a twenty-nine day month, the position of the various parts will be as shown in Figure 12 with the projection 122 engaging a pin 125 which is on the pin circle 126. Thus the arm 112 is shifted still further in a clockwise direction to bring the pin 117 closer to shoulder 118, or in other words to make the jaws open sooner. When the pin 108 reaches the position shown in dotted lines at 108-A in Figure 10, the pin 117 will have engaged the shoulder 118 to actuate shifting lever 119 and open the jaws as shown in Figure 9. The escapement wheel will then continue to move and the plate 101 will again be released when the pin reaches position 108-D as previously. In this case the hand 23 will have jumped from numeral twenty-nine to numeral one to begin indicating the days of the new month.

Assuming that a twenty-eight day month is to be indicated, the master gear will have assumed a position as shown in Figure 13 with projection 122 engaging a pin 127 on pin circle 128. This is the outermost pin circle and in this position, pin 117 will be in engagement with the shoulder 118 so that immediately upon pin 108 coming into engagement with lug 106 to start shifting the plate 101, the tripping lever 119 will be tripped to open the jaws 51 and 52 to release

the escapement mechanism. This will permit the escapement wheel to continue moving until plate 131 is released relative to pin 108, this being when the pin reaches position 108—D. In this case the hand 23 will have jumped from numeral twenty-eight to numeral one to begin indicating the next new month.

From the above description, it will be apparent that this invention provides an improved 10 horological device having a calendar mechanism for indicating the current "day of the week", "day of the month" and the "month of the year", in which the mechanism is so constructed that the date denoting indicia will be automatically 15 changed in such a manner as to compensate for "leap year" and the variations in the number of days in the respective calendar months; wherein the indicating means is moved with snap action; and in which the date indicating mechanism is so constructed that it may be utilized 20 as an attachment for a time indicating device such as a clock, and when so attached will be controlled by the time keeping device.

I am aware that many changes may be made 25 and numerous details of construction may be varied through a wide range without departing from the principles of this invention, and I, therefore, do not purpose limiting the patent granted hereon otherwise than necessitated by 30 the scope and spirit of the appended claims.

I claim as my invention:

1. In a device of the character described a cam member adapted to make a complete revolution each month, a first gear, a second gear, said 35 gears being coaxially mounted for limited relative rotation and elastically coupled, date indicating indicia successively indicated in response to the movement of said first gear, a releasable detent normally retaining said first gear against 40 movement, pawl means for advancing said second gear each revolution of said cam, and means responsive to the movement of said cam for releasing said detent subsequently to the advancement of said second gear, whereby the indicated 45 indicium is changed with a snap action.

2. In a device of the character described, a member carrying indicia corresponding to the respective days of a calendar month, means for successively changing the day of the month indicated, said means comprising an escapement, 50 a master gear intermittently advanced once each month, a plurality of pins carried by said gear and disposed at various radii from the center of said gear, a pivoted lever successively engaged 55 by said pins, the position of said lever depending upon the particular pin engaged, means for shifting said lever and gear as a unit about a common axis, and means engaged by said lever when so shifted for controlling the actuation of 60 said escapement.

3. In a horological device, an escapement including an oscillatable arm having a projection thereon, and means to control the starting and

stopping of the escapement, said means comprising a pair of latching jaws of different lengths pivoted at their inner ends to a common oscillatable support and connected for simultaneously opening when the longer of said jaws is pivoted 5 away from the other jaw, spring means resisting the opening of said jaws, said arm normally being latched against movement by the engagement of the projection with the outer end of the longer jaw, and means for oscillating said 10 support, movement of the support in one direction disengaging the longer jaw from the projection to enable it to engage the shorter jaw, movement of the support in the opposite direction bringing the longer jaw against said projection, whereby it is pivoted outwardly to open the jaws and release the escapement, the operation 15 of the escapement carrying the projection outwardly from between the jaws into latched position. 20

4. In a device of the character described, a member carrying indicia corresponding to the respective days of the calendar month, means for successively changing the day of the month indicated, said means comprising an escapement, 25 cam means intermittently advanced once each month, a cam follower having its position determined by said cam means, means for moving said cam means and follower as a unit, and means operable in response to said movement 30 for releasing said escapement.

5. In a device of the character described, a member carrying indicia corresponding to the respective days of a calendar month, means for successively changing the day of the month indicated, said means comprising an escapement, a rotatable cam member, a pivoted arm engaged by 35 said cam member, means for shifting said cam and arm as a unit about a common axis, means controlled by said arm during said shifting movement for releasing said escapement, and means responsive to said shifting movement for rotating said cam member a predetermined amount. 40

6. In a horological device, a movable member carrying indicia corresponding to the respective 45 days of a calendar month, and escapement means comprising an oscillatable pallet arm for controlling the movement of said member, a pair of latching jaws normally operable to release said arm for single indicium changes, and means for augmenting the operation of said jaws to release 50 said arm for plural indicium changes.

7. In a horological device, a movable member carrying indicia corresponding to the respective 55 days of a calendar month, and escapement means comprising an oscillatable pallet arm controlling the movement of said member, a pair of latching jaws successively operable to release said arm for single indicium changes, and simultaneously operable to release said arm for plural 60 indicium changes. 65

JOHAN MACHEK.
